UNITED STATES PATENT OFFICE.

JULIUS DÖRNETH, OF BERLIN, GERMANY, ASSIGNOR TO TYPOGRAPH G. M. B. H., OF BERLIN, GERMANY, A CORPORATION OF GERMANY.

TYPOGRAPH MATRIX-SETTING AND LINE-CASTING MACHINE.

1,414,775.

Specification of Letters Patent. Patented May 2, 1922.

Application filed October 27, 1914. Serial No. 868,858.

(GRANTED UNDER THE PROVISIONS OF THE ACT OF MARCH 3, 1921, 41 STAT. L., 1313.)

To all whom it may concern:

Be it known that I, JULIUS DÖRNETH, a subject of the German Emperor, and residing at Berlin, Germany, have invented certain new and useful Improvements in Typograph Matrix-Setting and Line-Casting Machines, of which the following is a specification.

My invention relates to improvements in typograph matrix setting and line casting machines, and more particularly to improvements in machines of the class shown and described in the patent of the United States No. 1,030,878 granted to me July 2, 1912, in which when setting mixed type the elevated matrix bars are supported on a strip or guide. The object of the improvements is to provide a machine of this class which is simple in construction and reliable in the operation of the movable parts, and in which the parts for moving the plate for elevating the matrices when setting special type are not liable to be soiled. With this and other objects in view my invention consists in the matters to be described hereinafter and particularly pointed out in the appended claims, reference being had to the accompanying drawings and to the letters of reference marked thereon. In said drawings

Figure 1, is a side elevation of the machine,

Fig. 1^a a view of a plural character matrix bar.

Fig. 2, is a plan view of the parts of the machine to which my invention more particularly relates,

Fig. 3, is a side view of Fig. 2 seen in the direction of the arrow I.

Fig. 4, is a similar side view seen in the direction of the arrow II, and

Figs. 5 and 6, are detail views.

The same letters of reference have been used in all the views to indicate corresponding parts.

For the purpose of explaining the invention I shall describe hereinafter a machine which is similar in construction to the machine shown in my above named patent. As the machine has been fully described in the said patent a brief description of the essential parts will be sufficient.

Referring to the drawings and firstly to Fig. 1, A designates the matrix basket rotatable about the axle *a*, and B the fixed

frame. By striking one of the keys *b* the corresponding matrix bar *d* having two matrices *m* and *m'* (see Fig. 1^a) and suspended above in the matrix basket is released by means of the wires *c*. The matrix slides along its guide wire *e* down to the collector where the line is assembled and is then cast. The basket is turned upward about the axle *a* by means of the grip *f* so that all the matrices slide back again.

When setting special types the matrix bars are elevated by means of a plate 10, and a strip or guide 1 is shifted into the path of the matrix bars the rear edges of which are formed with recesses adapted to be entered by the said strip or guide 1. For shifting the strip a slide 14 is provided which corresponds to the slide 14 shown in the patent to Dörneth, and which is adapted to be shifted to the right in Fig. 2 by means of a bar 12 as in my said Patent No. 1,030,878. When the slide 14 is shifted to the right a rod 11 is shifted which engages with teeth 2 formed thereon into the teeth of a gear wheel 3 secured to a rock shaft 4. By means of the rock shaft the plate 10 is rocked upwards together with the matrix bars supported thereon, as will be described hereafter. The rod 11 provides a locking member for a slide 5 which is acted upon by a spring 6 and which bears on the rod 11 with an arm 7. Therefore, if the rod 11 is shifted to the right, the shaft 4 is rocked and simultaneously the slide 5 is released, so that it is shifted by the spring 6 into the position shown in Fig. 2 in dotted lines. The slide 5 is connected with the strip 1 by a link 15 which is jointed to the strip by the bolt 41 and located angularly to the direction of the movement of the slide 5, so that the strip is pushed forwards when the slide 5 is released.

On a pivot bolt 16 secured to the side of the slide 5 a lever 17 has a rocking support which is formed with a shoulder 18 and is bent with its outer end 19 over the slide 5. Through the bent portion 19 a pin 20 is passed which is secured to the slide 5. Between the slide 5 and the bent portion 19 a spring 21 is interposed which tends to hold the lever 17 in its elevated position. When shifting the slide 5 forward the shoulder 18 engages a lever 22 having a rocking support on a pivot 23 so that the end of the lever 22 situated above the shoulder 18 is

lifted. The said end is connected by a jointed link 37 to a lever 38 pivoted about a point 38^a and on which is arranged a well-known holding pin *n* which has the function to 5 arrest the matrices supported on the plate 10 before they are assembled on the strip 1, as is known in the art. When the slide 5 moves forward, the lifting of the end of the lever 22 turns said lever about its pivot 23, 10 which gives the link 37 a slight movement to the left, whereby the lever 38 is moved leftwards and the pin *n* thrust in the path of the matrices. If, when a word is set, the spacer key is struck, the right end of 15 the lever 22 is depressed, whereby the above motion is reversed, the lever 38 being shifted to the right and the pin *n* withdrawn.

To the end of the shaft 4 which is opposite to the gear wheel 3 an arm 8 is secured which 20 engages a lug 9 provided on a depending arm 10' of the plate 10. The depending arm is formed with a guide slot 13 by means of which it is slidably mounted on a pin 42, and above the same a stop 4^a is provided 25 which is secured to a relatively fixed part. When rocking the shaft 4, the arm 8 assumes the position shown in broken lines in Fig. 5 and shifts the plate 10 forward, and when thus being shifted the plate is rocked about 30 the pin 42 by sliding along the stop 4^a so that the plate 10 is elevated into operative position. A spring 9^a retracts the plate out of operative position when the shaft 4 is returned into normal position. For returning 35 the shaft 4 into initial position a spring 24 is provided which is attached to the slide 11 and becomes operative when the bar 12 which acts on the slide 14 is rotated into initial position, the said spring shifting the 40 rod 11 back into setting position.

After setting and casting have been finished, and prior to distributing the matrix bars the strip 1 must be retracted. This is done by means of the mechanism by means 45 of which the matrix basket is automatically rocked into position for distributing the matrix bars. To the machine shaft a cam 25 is secured (Fig. 6) which engages a roller 28 mounted on a rocking lever 26— 50 27—29, 30. The arm 30 of the said lever is formed with a nose 31 which is located in position for engagement with an angular plate 32 secured to the slide 5. If the matrix bars are being automatically distributed, the 55 nose 31 shifts the slide 5 backwards and into position for being locked by the rod 11.

If it is desired to take several casts from the same line, the lever 26, 27 is brought into the position shown in Fig. 6 in dotted lines, 60 and the lever 29, 30 is rocked into the position in which the nose 31 engages above the plate 32, so that the levers 26 to 31 are held in the inoperative positions.

To the strip 1 an arm 33 is secured, and 65 the rack 34 by means of which the machine

is thrown into operation (rack 34 corresponding to arm 7 in Patent No. 1,030,878) is provided with an arm 35 which carries a spring actuated pin 36 projecting above the arm 33. When the strip 1 has been advanced sufficiently the pin 36 can pass along the arm 33. But if the strip has not been shifted completely into projected position, as may be prevented for example by particles of lead or the like, the pin 36 is arrested by the arm 33, so that the toothed rack 34 can not move downwards and the machine can not be thrown into operation.

I claim herein as my invention:

1. In a matrix setting and line casting machine, the combination with the matrix bars each having a plurality of type matrices formed thereon, and guiding members for assembling and distributing the matrix bars, of a shiftable strip providing a support for the matrix bars for holding the same in set position when setting special type, a slide movable in a direction substantially perpendicular to the shiftable strip, a link connecting said strip and slide and disposed at an angle to the direction of the movement of the slide, and operating means for the slide.

2. In a matrix setting and line casting machine, the combination with the matrix bars each having a plurality of type matrices formed thereon, and guiding members for assembling and distributing the matrix bars, of a shiftable strip providing a support for the matrix bars for holding the same in set position when setting special type, a spring actuated slide movable in a direction substantially perpendicular to the shiftable strip, a link connecting said strip and slide and disposed at an angle to the direction of the movement of the slide, a shiftable member normally locking said slide in inoperative position, operating means for throwing the slide in non-locked position, means for returning the member into locking position, and means automatically controlled from the machine shaft when distributing the matrix bars for returning said slide and strip into normal positions.

3. In a matrix setting and line casting machine, the combination with the matrix bars each having a plurality of type matrices formed thereon, and guiding members for assembling and distributing the matrix bars, of a shiftable strip providing a support for the matrix bars for holding the same in set position when setting special type, a spring actuated slide movable in a direction substantially perpendicular to the shiftable strip, a link connecting said strip and slide disposed at an angle to the direction of the movement of the slide, a shiftable member normally locking said slide in inoperative position, operating means for throwing the slide in non-locked position, means for returning the member into lock-

ing position, means automatically controlled from the machine shaft when distributing the matrix bars for returning said slide and strip into normal positions, and a member 5 connected with said means for throwing said means out of operative position.

4. In a matrix setting and line casting machine, the combination with the matrix bars each having a plurality of type matrices 10 formed thereon, guiding members for assembling and distributing the matrix bars, of a shiftable strip providing a support for the matrix bars for holding the same in set position when setting special type, a spring actuated slide movable in a direction substantially perpendicular to the shiftable strip, a link connecting said strip and slide and disposed at an angle to the direction 15 of the movement of the slide, a shiftable member normally locking said slide in inoperative position, operating means for throwing the slide in non-locked position, means for returning the member into locking position, a plate for lifting the matrix bars, means operated by the shiftable member 20 for rocking said plate with the matrix bars in lifted position, and means automatically controlled from the machine shaft when distributing the matrix bars for returning said slide and strip into normal positions.

5. In a matrix setting and line casting machine, the combination with the matrix bar each having a plurality of type matrices 35 formed thereon, and guiding members for assembling and distributing the matrix bars, of a shiftable strip providing a support for the matrix bars for holding the same in set position when setting special type, a spring actuated slide movable in a direction substantially perpendicular to the shiftable strip, a link connecting said strip and slide and disposed at an angle to the direction 40 of the movement of the slide, a shiftable member normally locking said slide in inoperative position, operating means for throwing the slide in non-locked position, means for returning the member into locking position, a plate for lifting the matrix bars, means operated by the shiftable member 45 for rocking said plate with the matrix bars in lifted position, holding pins for holding the matrix bars being assembled on said plate prior to admitting the same to the strip, an operative connection 50 between said holding pins and slide for throwing the pins in holding position,

means tending to retract the pins out of holding position, and means automatically controlled from the machine shaft when 60 distributing the matrix bars for returning said slide and strip into normal positions.

6. In a matrix setting and line casting machine, the combination with the matrix 65 bars each having a plurality of type matrices formed thereon, and guiding members for assembling and distributing the matrix bars, of a shiftable strip providing a support for the matrix bars for holding the 70 same in set position when setting special type, a spring actuated slide movable in a direction substantially perpendicular to the shiftable strip, a link connecting said strip and slide and disposed at an angle to the 75 direction of the movement of the slide, a shiftable member normally locking said slide in inoperative position, operating means for throwing the slide in non-locked position, means for returning the member 80 into locking position, a plate for lifting the matrix bars, means comprising a rock shaft and a gear wheel mounted thereon and operated by the shiftable member for rocking said plate with the matrix bars in 85 lifted position, and means automatically controlled from the machine shaft when distributing the matrix bars for returning said slide and strip into normal positions.

7. In a matrix setting and line casting 90 machine, the combination with the matrix bars each having a plurality of type matrices formed thereon, and guiding members for assembling and distributing the matrix bars, of a shiftable strip providing a support for the matrix bars for holding the same in set position when setting special type, shifting means for said strip, mechanism for throwing the machine into operation, and a member connected with the 95 mechanism and located in position for locking engagement with the strip when the latter has not been shifted completely into position for providing a support for the matrix bars, said member being inoperative when the strip is in completely projected position.

In testimony whereof I hereunto affix my signature in the presence of two witnesses.

JULIUS DÖRNETH.
